UNITED STATES PATENT OFFICE

100,974

DESIGN FOR A TRAFFIC BUTTON

John W. Shaffer and Ralph T. Phillips, Minneapolis, Minn., assignors to John W. Shaffer & Company, a corporation of Minnesota

Application July 13, 1936, Serial No. 63,827

Term of patent 14 years

To all whom it may concern:

Be it known that we, John W. Shaffer and Ralph T. Phillips, citizens of the United States, residing at Minneapolis, in the county of Hennepin and State of Minnesota, have invented a new, original, and ornamental Design for a Traffic Button, of which the following is a specification, reference being had to the accompanying drawing, forming part thereof, and in which

Figure 1 is a top plan view of a traffic button showing our new design;

Figure 2 is a side elevational view; and
Figure 3 is an end view thereof.

We claim:

The ornamental design for a traffic button, as shown.

JOHN W. SHAFFER.
RALPH T. PHILLIPS.
